EVACUATOR

William C. Groeniger, Columbus, Ohio, assignor
to John B. Pierce Foundation, New York, N. Y.,
a corporation of New York

Application February 2, 1935, Serial No. 4,620

10 Claims.

(Cl. 4—69)

My present invention relates to evacuators.

Embodiments of my present invention, designated evacuators, possess characteristics of the general nature of half-syphon legs, that is to say, function to form the posterior leg of a syphon, the anterior leg of which is constituted of an upwardly extending passage with which my evacuator is connected, and serving therewith to discharge a defecator.

Preferably, the anterior or upwardly extending passage is constituted of an upwardly extending passage formation of the defecator, preferably also of the lateral outlet type, such as is disclosed in my co-pending application Serial #733,259, filed June 30th, 1934, and entitled Lateral outlet defecator.

My invention may also be applicable to the type of lateral outlet defecator set forth and claimed in my co-pending application Serial #749,069, filed October 19th, 1934, and entitled Defecator.

The general characteristics of my evacuator, embodying my present invention, reside in an uppermost portion arranged to be detachably connected to the uppermost portion i. e., discharge of an upwardly extending leg of a lateral outlet type of defecator or to the uppermost portion i. e., discharge of an upwardly extending anterior syphon leg of a non-lateral outlet type of defecator. Such uppermost portion includes a weir serving per se as or in conjunction with a wall of the uppermost portion of the anterior syphon passage or leg, as a dam. The uppermost portion of the evacuator further includes a bulged or elbow formation, whereby upon flow of the effluent discharged from the defecator, a portion of the quantity of air originally in the bulged or elbow formation, is entrained, thereby giving rise to sub-atmospheric pressure of the retained air. My evacuator further includes a downwardly extending central or other intermediate portion, the effective cross-sectional area of which is less than that of the uppermost portion of the evacuator, thus providing for a relatively restricted cross-sectional area of the effluent flowing through such intermediate portion. My evacuator preferably includes supplemental portions disposed lower relative to its stated intermediate portion, an essential characteristic of which is that the effluent assumes the form of a flowing curtain and other therewith comparable formation serving to preclude the inflow of air through the lower or discharge opening of the defecator during the stage of syphonic discharge of the effluent.

The lower or discharge end of my evacuator is connected with a soil pipe, or other suitable passage means, for affording the discharge of the effluent therein.

Further features and objects of the invention

will be more fully understood from the following detail description and the accompanying drawings, in which

Fig. 1 illustrates my evacuator in assembly with a preferred type of defecator, and is a vertical section taken on line 1—1 of Fig. 2; Fig. 2 is a top plan view of the evacuator shown in Fig. 1.

Fig. 3 is a side elevation of Fig. 2.

Fig. 4 is a vertical section on line 4—4 of Fig. 5 and Fig. 5 is an elevation of another embodiment of evacuator, pursuant to my present invention.

Fig. 6 is a sectional elevation on line 6—6 of Fig. 7 and Fig. 7 is an elevation of another embodiment of my invention.

Fig. 8 is a view similar to Fig. 1 illustrating an initial stage of discharge of the contents of the indicated defecator through my evacuator. Fig. 9 is a similar view illustrating a later stage 20 of the discharge. Fig. 10 is a similar view showing a still later stage of the discharge. Fig. 11 is a similar view illustrating the stage of the "breaking" of the syphonic action. Fig. 12 is a detail elevation on line 12—12 of Fig. 8. 25

Referring to the embodiment shown in Figs. 1, 2 and 3, the type of evacuator 40 comprises an uppermost or inlet portion 41 suitably secured within the discharge opening 20 of the defecator, such as the type of defecator 10 indicated in Fig. 1, and corresponding in construction to the type of defecator described and claimed in my aforesaid co-pending application Serial #749,069, entitled Defecator. Briefly, such defecator comprises in its essentials an up-flow, i. e., anterior syphon half-leg 15, its inlet 15a being disposed proximate the lowermost edge 18a of the inwardly disposed ledge 18 which extends downwardly toward the well portion 12 of the bowl; 35 preferably, the lowermost level 12a of the bottom of the well 12 is disposed interiorly of the opening 15a of the anterior syphon half-leg 15. The dam or weir of the anterior syphon half-leg is indicated at 16, the effective face of which is 40 substantially level, i. e., in alignment with the lower face 41a of the inlet 41 of the evacuator 40. 45

For the purpose of fuller explanation of the showing of Fig. 1, the inflow port of the water or other effluent is indicated at 23, leading to 50 the main water channel 22, thence through the port 31 leading to the channel 30 for the supply of the main discharge jet (not shown) and for the supply at a predetermined time interim to the rim jets 28. Such bowl may or may not be 55 provided with a vortex effecting jet (not shown), also supplied from the main water channel 22. The afterfill 13 serves as the effluent for receiving the solid, liquid and other matter to be discharged from the defecator, the normal level 60

14 of such effluent being determined by the vertical height of the dam or weir 16.

The type of evacuator shown in Figs. 1, 2 and 3, embodies a relatively thick wall at its inlet 41, the thickness of which is determined by the contour of the discharge opening 29 of the defecator. Such relatively thickened wall of the opening 41 is shown of solid formation.

The support of the defecator is preferably had 10 independently of the connection of the evacuator with the defecator, as by means of bolts passing through the upper portion of the rear wall of the defecator, i. e., on opposite sides of the ledge 24a at the rear of the upper face of the bowl.

15 A preferred form of mechanically securing the connection of the inlet opening of the evacuator 40 relative to the discharge opening of the defecator is set forth and claimed in my co-pending application Serial #48,860 filed Nov. 8th, 1935, 20 entitled Plumbing connection.

16 The opening of the inlet 41 leads to the upper section extending directly from the inlet 41 horizontally and communicating directly with the upper elbow section 42 of the evacuator, the 25 lower end of which communicates with a downwardly extending cross-sectional slightly restricted section 43, thence to the lowerly disposed effluent-curtain-forming section 44. The outtake section 45 is adapted to be connected in 30 any suitable manner to a Y-fitting or other laterally opening fitting leading to a soil pipe, waste pipe, etc.

17 As appears from Figs. 2 and 3, the evacuator desirably has a general Z formation, to most 35 effectually attain the above stated functions of the respective sections of the evacuator, also a predetermined length of travel, improved manner of connection of the outtake section with the Y or other laterally opening fitting, etc.

18 As appears from Fig. 2, the type of evacuator 40 is of the 45° angle, but may be of a 90° angle, zero angle or any intermediate angle, as preferred.

19 The type of evacuator shown in Figs. 4 and 5 corresponds in essentials to the type shown in 45 Figs. 1, 2 and 3, and like parts are designated by like reference characters. It will be noted that the evacuator shown in Figs. 4 and 5 is of the zero angle type.

20 The evacuator shown in Figs. 4 and 5 illustrates in particular the formation of the wall of the evacuator of substantially uniform thickness, the enlarged diameter at its intake 41 being had by an outer annular thimble 41b, secured at its 55 reduced end 41c to the exterior of the wall of the intake 41 by welding, brazing, etc. Its outtake wall formation 45 may be had by a separate member secured at its reduced end 45a to the juxtaposed end of the section 44, as by welding, brazing, etc.

21 The evacuator shown in Figs. 6 and 7, is of the 90° angle type, and its parts corresponding to the parts of the evacuator shown in Figs. 1, 2 and 3 are designated by like reference characters.

22 My evacuator of the type shown in Figs. 4 and 5 may be made of sheet metal suitably contoured in the drawing operations of the same.

23 The type of evacuator shown in Figs. 6 and 7 may be cast.

24 Figs. 8 through 12 illustrate a typical manner of operation of my evacuator. In Fig. 8 is depicted the initial stage induced primarily by the main discharge jet of the discharge of the effluent 13 from the defecator 10 upwardly through 70 the anterior syphon half-leg 15, the portion of

the effluent within the bowl proper being preferably subjected to a vertical movement, say in counter-clockwise direction as viewed from above. Under such or equivalent condition the mean vertical height of the effluent within the bowl proper 5 is maintained substantially at the level 14, compare with Fig. 1, the peripheral portion of the effluent being elevated by reason of the centrifugal force imparted thereto by the vertical movement, the central portion of the effluent within 10 the bowl proper being relatively depressed, thus creating, inter alia, a positive force radially inwardly toward such central and depressed portion of the effluent upon floating and semi-floating manner and in a direction downwardly toward 15 the inlet 15a of the anterior, i. e., upwardly directed syphon half-leg 15. Such initial movement effects a rise of the effluent above and over the weir 16 and the lower wall portion 41a 20 of the uppermost section of the evacuator 40, 25 whereby the effluent passes over the ledge 41d, see also Fig. 12, the effluent upon flowing thereover forming a curtain 46 flowing over and in cooperation with the downwardly extending wall 47 of the intermediate section of the evacuator 40, 25 ultimately reaching the lowermost section 44. Such curtain-like formation 46 of the effluent and its downward flow entrains air originally at atmospheric pressure in the upper bulged or elbow 30 section 42, and as appears hereinafter, the continuance of such curtain-like flow entrains more and more of the stated air and thus more and more reduces its volume and correspondingly reduces the pressure of the air remaining in such bulged or elbow section 42 to lower and lower 35 sub-atmospheric pressure values.

Fig. 9 illustrates a later stage of the flow of the effluent, whereat the cross-sectional area of the curtain-like formation 46 is increased, accompanied by increased entrainment of the 40 stated air in the region 42, as above referred to. As is observed from Fig. 8, initially a pool 44a of the effluent is formed within the section 44, which advantageously is of a flat dish-like formation, such pool 44a co-acting with the curtain-like 45 formation of the effluent to form a seal against the entry of air through the section 45 in a direction counter to that of the flow of the effluent, which otherwise would retard or "break" the 50 syphonic action.

Fig. 10 illustrates the status of the discharge of the effluent through my evacuator at a stage of substantially full discharge, the curtain-like formation 46 of the effluent substantially completely filling the intermediate section 43 of the 55 evacuator.

As referred to above, the cross-sectional area of the intermediate or central section 43 of my evacuator 40 is preferably less than that of upwardly disposed sections, whereby a predetermined relative reduction of the rate of travel of the effluent is brought about, thus effecting and maintaining a substantially complete filling by the effluent at the region adjacent the ledge portion 41d and the greater part of the volume 60 of the bulged or elbow portion 42, such action serving to increase the rate of entrainment of the air within the stated bulged or elbow portion 42. At the stage illustrated in Fig. 10, i. e., of substantially full syphonic action, the contents 70 of the bowl are effectually discharged therefrom through my evacuator. It will be observed that throughout the respective stages typified in Fig. 8, in Fig. 9 and in Fig. 10, the entry of air through the effluent outtake 45 in a direction counter to 75

that of the flow of the effluent, is wholly precluded.

The discharge of the effluent from the bowl proper, succeeding the stage indicated in Fig. 10, continues until the level 14a, see Fig. 11, of the effluent 13 within the bowl proper subsides below the lower edge 18a of the ledge 18 disposed inwardly of the bowl proper, at which stage air from the interior of the bowl proper enters in the direction indicated by the arrows 48, thus breaking the syphonic action, followed by consequent subsiding of the effluent in the region of the dam 16 and ledge 41d, accompanied by a partial return flow of the effluent then within the anterior 15 syphon up-flow leg 15, which commingles with the effluent supplied through the rim openings 28 to form the afterflow, preparatory for a subsequent operation of the defecator.

In the type of evacuator shown in Figs. 8 through 11 as also in the type shown in Figs. 1, 2 and 3, the wall portion 47 of the central or intermediate section 40 may be of flat-wise formation, to enhance the adherence thereto of the curtain-like formation 46 of the effluent. Such enhanced action may also be attained by contouring the intermediate portion of the defecator re-entrantly, as is indicated in Fig. 4; the section of minimum cross-sectional area indicated at 43a, of the type shown in Figs. 4 and 5 is disposed more 30 lowerly as compared with the type of evacuator shown in Figs. 8, 9, 10 and 11, and likewise with respect to the type illustrated in Figs. 1, 2 and 3.

The type shown in Figs. 6 and 7, attains such enhanced operation of the curtain-like formation 46 of effluent by means of a substantially rectilinearly extending intermediate section 43 which also tilts with respect to the vertical.

As is observed from the drawings, in particular Figs. 7 and 12, the cross-section of the horizontally extending upper portion of my evacuator is advantageously of elliptical cross-section, a relatively flat face of such elliptical cross-section coinciding with the horizontal flat weir or dam 16 of the syphon up-flow leg, thus affording free 45 entry of the effluent into and through the horizontal upper section of my evacuator and attendant increased flow of the effluent into and through the downwardly extending elbow 42, accompanied by the formation of the curtain at the ledge 41d, 50 and correspondingly through the subsequent co-acting flow phases, referred to hereinabove.

From the above, it appears that embodiments of my invention effect the flow of the effluent to form water dams and curtains at sequentially related locations, positively created and maintained by the construction and relative arrangement of the respective sectional parts of my evacuator, the passage of the effluent into and through my evacuator being at all times unobstructed as to 60 the flow of the effluent—thus in marked superiority over the prior art “water-plug” principle—but at all stages of the forming and existence of the syphonic action the flow of air into the interior of the evacuator is positively precluded by the 65 stated water dams and curtains.

Whereas I have described my invention by reference to specific forms thereof, it will be understood that many changes and modifications may be made without departing from the spirit of the 70 invention.

I claim:

1. As an article of manufacture, a posterior syphon half-leg provided with intake and outtake openings, comprising an upper section communicating directly with the intake opening and

extending wholly horizontally therefrom, an upper elbow section communicating directly with said upper horizontally extending section, said elbow section being of relatively large cross-sectional area, said article further comprising a lower downwardly extending section of relatively lesser cross-sectional area, the walls of said article being imperforate between its intake and outtake openings. 5

2. As an article of manufacture, a posterior syphon half-leg provided with intake and outtake openings, comprising an upper section communicating directly with the intake opening and extending wholly horizontally therefrom, an upper elbow section communicating directly with 15 said upper horizontally extending section, said elbow section being of relatively large cross-sectional area, said article further comprising a lower section of relatively lesser cross-sectional area extending downwardly in mean direction at 20 an angle to the vertical, the walls of said article being imperforate between its intake and outtake openings.

3. As an article of manufacture, a posterior 25 syphon half-leg provided with intake and outtake openings, comprising an upper section communicating directly with the intake opening and extending wholly horizontally therefrom, an upper elbow section communicating directly with 30 said upper horizontally extending section, said elbow section being of relatively large cross-sectional area, said article further comprising a lower downwardly extending section of relatively lesser cross-sectional area, said article further 35 comprising a lowermost section extending horizontally, the walls of said article being imperforate between its intake and outtake openings.

4. As an article of manufacture, a posterior 40 syphon half-leg provided with intake and outtake 45 openings, comprising an upper section communicating directly with the intake opening and extending wholly horizontally therefrom, an upper elbow section communicating directly with 50 said upper horizontally extending section, said elbow section being of relatively large cross-sectional area, said article further comprising a lower section of relatively lesser cross-sectional area, extending downwardly in mean direction at 55 an angle to the vertical, said article further comprising a lowermost section extending horizontally, the walls of said article being imperforate between its intake and outtake openings.

5. As an article of manufacture, a posterior 60 syphon half-leg provided with intake and outtake 65 openings, comprising an upper section communicating directly with the intake opening and extending wholly horizontally therefrom, an upper elbow section communicating directly with 70 said upper horizontally extending section, said elbow section being of relatively large cross-sectional area, said article further comprising a lower downwardly extending section of relatively lesser cross-sectional area, said lower section including a portion having a flat wall formation, the walls of said article being imperforate between its intake and outtake openings.

6. As an article of manufacture, a posterior 75 syphon half-leg provided with intake and outtake openings, comprising an upper section communicating directly with the intake opening and extending wholly horizontally therefrom, an upper elbow section communicating directly with 80 said upper horizontally extending section, said elbow section being of relatively large cross-sectional area, said article further comprising a lower 85

- downwardly extending section of relatively lesser cross-sectional area, said lower section including a portion having a flat wall formation, said article further comprising a lowermost section extending horizontally, the walls of said article being imperforate between its intake and outtake openings.
7. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said article further comprising a lowermost section extending horizontally, said lowermost section having a dish-like lower wall formation, the walls of said article being imperforate between its intake and outtake openings.
8. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower downwardly extending section of relatively lesser cross-sectional area, said lower section including a portion having a flat wall formation, said lowermost section having a dish-like lower wall for-

mation, the walls of said article being imperforate between its intake and outtake openings.

9. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower section of relatively lesser cross-sectional area extending downwardly in mean direction at an angle to the vertical, said lower section including a portion having a flat wall formation, the walls of said article being imperforate between its intake and outtake openings.

10. As an article of manufacture, a posterior syphon half-leg provided with intake and outtake openings, comprising an upper section communicating directly with the intake opening and extending wholly horizontally therefrom, an upper elbow section communicating directly with said upper horizontally extending section, said elbow section being of relatively large cross-sectional area, said article further comprising a lower section of relatively lesser cross-sectional area extending downwardly in mean direction at an angle to the vertical, said article further comprising a lowermost section extending horizontally, said lower section including a portion having a flat wall formation, said lowermost section having a dish-like lower wall formation, the walls of said article being imperforate between its intake and outtake openings.

WILLIAM C. GROENIGER.
